US00D899710S

(12) **United States Design Patent** (10) **Patent No.:** **US D899,710 S**
MacDonald (45) **Date of Patent:** **** Oct. 20, 2020**

(54) **FLEXIBLE STRAP FOR A HOOF BOOT**

(71) Applicant: **ScootBoot Pty Ltd**, Koonya, Tasmania (AU)

(72) Inventor: **David Duncan MacDonald**, Tasmania (AU)

(73) Assignee: **SCOOTBOOT PTY LTD**, Tasmania (AU)

(**) Term: **15 Years**

(21) Appl. No.: **29/677,621**

(22) Filed: **Jan. 22, 2019**

(30) **Foreign Application Priority Data**

Jul. 23, 2018 (AU) 201814399

(51) **LOC (12) Cl.** **30-01**

(52) **U.S. Cl.**

(57) **CLAIM**

The ornamental design for a flexible strap for a hoof boot, as shown and described.

DESCRIPTION

FIG. 1 is a perspective view of a flexible strap for a hoof boot showing the new design.

FIG. 2 is a front view thereof.

FIG. 3 is a rear view thereof.

FIG. 4 is a right side view thereof, the left side view being a mirror image thereof.

FIG. 5 is an enlarged top view of the flexible strap for a hoof boot; and,

FIG. 6 is a bottom view thereof.

The broken lines depict portions of the flexible strap for a hoof boot that form no part of the claimed design.

1 Claim, 6 Drawing Sheets
